UNITED STATES PATENT OFFICE.

BENJAMIN J. GREER, OF ATHENS, TEXAS.

LOCK.

Application filed May 2, 1923. Serial No. 636,090.

To all whom it may concern:

Be it known that I, BENJAMIN J. GREER, a citizen of the United States, and a resident of Athens, in the county of Henderson 5 and State of Texas, have invented certain new and useful Improvements in Locks, of which the following is a full, clear, and exact description.

My invention relates to improvements in combination locks, and one of the objects of the invention is to provide a lock of this character which is most simple in construction and hence inexpensive in manufacture.

Another object of the invention is to provide a combination lock which is entirely safe, and which is capable of almost an infinite number of combinations.

A further object of the invention is to provide a lock of this character which is formed of such a small number of parts that it is practically impossible for the lock to get out of order.

Still another object of the invention is to provide a lock so constructed that it is impossible to feel out the combination.

Other and further objects and advantages of the invention will be apparent to those skilled in the art from the following detailed description.

For a complete illustration of the invention reference is to be had to the accompanying drawings, in which:

Figure 1 is a perspective view of the lock in closed position.

Figure 2 is a vertical transverse sectional view, taken through the body of the lock.

Figure 3 is a horizontal sectional view taken on the line 3—3 of Figure 2.

Figure 4 is a vertical sectional view taken on the line 4—4 of Figure 2.

Figure 5 is a vertical sectional view taken on the line 5—5 of Fig. 2; and

Figure 6 is a detail view of one of the locking screws and a portion of the staple.

Referring to the drawings more in detail, numeral 1 indicates the body of the lock, which is adapted to receive the two legs 2 and 3 of the sliding shackle 4. To permit a sliding movement of the shackle and yet prevent its withdrawal from the lock body, the longer leg 2 of the shackle is provided with a cut-out portion 5, and a pin 6 is mounted in the lock body in position to co-operate with the cut-out portion.

Each leg of the shackle is provided with a pair of grooves 7, and the grooves in the two legs are alined, as clearly shown in the drawings. The body of the lock is provided with suitable passages for the introduction 60 of a U-shaped member 8, which will hereafter be termed a staple, and each leg of this U-shaped member or staple co-operates with the grooves 7 in the shackle, thereby locking the shackle against longitudinal 65 movement. It will be noted that one leg of the staple is of sufficient length to extend beyond the lock body, as indicated by numeral 9; the purpose being to present means for pushing the staple free of the 70 body when the shackle is to be withdrawn.

I will now describe the means by which the staple is locked in its operative position.

Each leg of the staple is provided with a plurality of pairs of oppositely disposed 75 grooves 10, there being three pairs of these grooves shown in the drawings. These grooves are preferably, though not necessarily, screw threaded, as indicated by numeral 11 on Figure 6.

The body of the lock is provided with a plurality of vertical passages 12, the walls of which are screw threaded, and mounted in each of these passages is a locking screw 13. The locking screws are provided with 85 oppositely disposed grooves 14, and when the locking screws are in the proper position these grooves will co-operate with the staple to permit withdrawal thereof.

Mounted in the lower portion of the lock body is a member 15, which performs a dual function. The member 15 is provided at both the top and bottom with a pair of inwardly extending flanges; the flanges at the top being indicated by numeral 16, and those at the bottom being indicated by numeral 17. The flanges 16 project slightly over the open ends of the passages 12 and thereby prevent the removal of the locking screws. The flanges 17 co-operate with the shank 100 of the key 18, and these flanges, in conjunction with the collar 19 provided on the key, prevent removal of the key. Of course, the bottom wall of the lock body is provided with a slot to permit the key to be moved transversely of the lock to operate the various locking screws; the slot being indicated by numeral 20.

The operation of the device will be clearly understood from the foregoing description.

To secure the parts in locked position, the shackle 4 is first pushed in and then the staple 8 is inserted; the legs of the staple entering the grooves 7 in the shackle and thereby preventing withdrawal of the shackle. The locking screws 13 are now given a few turns and the body of the locking screws will enter the grooves 10 in the staple, thereby preventing withdrawal of the staple.

To unlock the parts each locking screw must be given a sufficient number of turns, or fractions thereof, so that the grooves 14 will come into position to free the staple 8. It is obvious that a very fine adjustment of the locking screws is necessary, for it is not only necessary that they be correctly positioned longitudinally, but also their angular position must be correct, in order that the grooves 14 will be in proper position to release the staple. It will be understood, of course, that in actual practice the combination, or number of turns and fractions thereof for each screw, will be determined from the extreme upper or lower position of the screws. When the locking screws are in position to release the staple the same is withdrawn; thereby freeing the shackle and permitting the opening of the lock.

From the foregoing description it will be apparent that I have devised a lock that is most simple in construction and inexpensive in manufacture; that is entirely safe; that is capable of almost an infinite number of combinations; and that is so constructed that it is impossible to feel out the combination.

In accordance with the patent statutes, I have described what I now believe to be the best embodiment of the invention, but I do not wish to be understood thereby as limiting myself or the scope of the invention, as many changes and modifications may be made without departing from the spirit of the invention; all such I aim to include in the scope of the appended claims.

What I claim as new and desire to secure by Letters Patent is:

1. A lock, including a body and a shackle, one leg of the shackle being provided with a groove, a member slidably mounted in the body, said member adapted to enter the groove in the shackle, said member also provided with grooves, and locking screws adapted to engage said grooves.

2. A lock, including a body and a shackle, the legs of the shackle being provided with alined grooves, a member slidably mounted in the body, said member adapted to enter the alined grooves in the shackle, said member also provided with grooves, and locking screws adapted to engage said grooves.

3. A lock, including a body and a shackle,

one leg of the shackle being provided with grooves on the opposite sides thereof, a U-shaped member slidably mounted in the body, said U-shaped member adapted to enter the grooves in the shackle leg, said U-shaped member also provided with grooves, and locking screws adapted to engage said grooves.

4. A lock, including a body and a shackle, the legs of the shackle provided with oppositely disposed alined grooves, a U-shaped member slidably mounted in the body, said U-shaped member adapted to enter the oppositely disposed alined grooves, said U-shaped member also provided with grooves, and locking screws adapted to engage said grooves.

5. A lock, including a body and a shackle, a slidale staple adapted to engage the shackle to prevent movement thereof, and combination means engaging the slidale staple.

6. A lock, including a body and a shackle, a slidale staple adapted to engage the shackle to prevent movement thereof, one end of the slidale staple extending beyond the lock body for the purpose specified, and combination means engaging the staple.

7. A lock, including a body and a shackle, a slidale member adapted to engage the shackle to prevent movement thereof, the slidale member provided with a plurality of grooves, and locking screws adapted to engage the grooves, said locking screws also provided with grooves, whereby the slidale member is released when the grooves in the locking screws aline with the grooves in the slidale member.

8. A lock, including a body and a shackle, the legs of the shackle provided with oppositely disposed alined grooves, a U-shaped member slidably mounted in the body, said U-shaped member adapted to enter the oppositely disposed alined grooves, said U-shaped member also provided with grooves, locking screws adapted to engage the grooves in the U-shaped member, said locking screws also provided with grooves, whereby the U-shaped member is released when the grooves in the locking screws aline with the grooves in the U-shaped member.

9. In a lock, a body, said body provided with a plurality of vertical passages, locking screws mounted in the passages, flanges extending partly over the open ends of the passages, thereby preventing removal of the locking screws, a U-shaped member adapted to be engaged by the locking screws, and a shackle adapted to be engaged by the U-shaped member.

BENJAMIN J. GREER.
